JOHN A. HOFFMAN, OF PAINESVILLE, OHIO, ASSIGNOR TO THE CUYAHOGA SPRING COMPANY.

PROCESS OF MAKING SPRING CLIPS.

Application filed May 4, 1923. Serial No. 636,722.

This invention relates to a method of making wire forms and particularly small spring clips. The formation of spring clips is frequently accomplished by forming loops and ends thereof in two or three planes at angles to each other, from a single strip of wire. The wire is given a series of successive bending operations by cams and pusher members acting upon said piece of wire 10 while held in a single form, so that when the successive operations have been performed a predetermined form of clip is made in a single machine, and without the necessity of transferring the device from one 15 set of dies to another.

It is an object of the present invention to perform the usual steps of forming a clip, having looped side and end portions in three planes, of a single piece of wire, and while 20 being acted upon and held in the same form to additionally bend a portion of the clip out of its plane. Thus, by the present invention in a single machine, a wire may be cut, bent to form a loop in one plane, portions there- 25 of turned at right angles thereto in another plane, and portions again turned, while in the same form into substantial parallelism with the first-formed loop, and thereafter while still so held, the latter portion being 30 given a certain bend or offset as may be desired.

The general object of the invention is to make a spring clip of the general character described, which normally requires six operations, without transferring the clip, either 35 manually or automatically, from one set of dies to another, but to so arrange the series of steps of formation that they may be all accomplished while the wire is held in sub- 40 stantially one place in a single machine.

The invention is made more clear in the following description which relates to the drawing illustrating a particular form of spring clip to which the steps of the process 45 are particularly adapted and for which they are designed, and the essential characteristics of my invention are set forth in the claims.

In the drawings, Fig. 1 is a perspective view of the essential parts of a group of wire bending dies adapted to act upon a piece of wire in successive steps in six directions, that is, in four directions in one substantially horizontal plane and in an up- 50 and downward direction from below

and above respectively; Fig. 2 is a plan view of a group of the dies performing the first step of forming the spring clip; Fig. 3 is a similar view showing the parts acting upon the wire; Fig. 4 is a similar view of these 60 same parts showing the next step of action on the wire; Fig. 5 is a vertical transverse section showing the means for turning upwardly the side portions of the clip, the plane of the section being along the plane 65 indicated by the line 5—5 of Fig. 2; Fig. 6 is a horizontal plan view of the acting parts of cams moving in from opposite sides at substantially right angles to the direction 70 of the action of the parts in Figs. 2, 3 and 4; Fig. 7 is a vertical section taken substantially on the line 7—7 of Fig. 6; Fig. 8 is a similar section showing the last step of acting upon this clip, this figure being taken 75 substantially on a plane corresponding to the line 8—8 of Fig. 6; Figs. 9, 10, 11, 12 and 13 show the different stages illustrating the steps of my process for forming the spring clip, illustrated in finished form in Fig. 13; Fig. 14 is a fragmentary detail on a somewhat enlarged scale showing the upper end of a spark plug and the terminal leading thereto secured by the spring clip of Fig. 13, thus illustrating the purpose of such a clip. 80

In order to illustrate the process of the present invention most conveniently, I will first describe the particular form of spring clip shown in Figs. 13 and 14. It has a looped portion L adapted to surround the screw or cap of a spark plug P, the loop 90 being open at one side to permit of the spring clip being thrust thereupon transversely of the head of the spark plug, and these looped ends being integral with the laterally extending loops M in a plane at 95 right angles to the loop L, which turn inwardly and again have clamping finger portions formed of the same wire as indicated at O. These clamping portions are adapted to embrace a flat lead wire terminal and are curved to facilitate thrusting the terminal thereunder. 100

To further illustrate the steps of my process, I have shown in Figs. 1 to 8 suitable dies and forming members which will now be 105 briefly described. In Fig. 1, a block 1 in the nature of an anvil member is provided with vertical slideway openings therethrough in which are mounted slidably, a substantially cylindrical member 2 having a laterally ex- 110

tending wing adapted to form a slide in the block 1. Over this member the wire is bent to form the looped portions L and O, as will presently appear. A suitable wire guide 15 leads the wire W across this rail member 2, substantially as shown in Fig. 1, thereupon by transverse movement a pair of forming dies 10, having the end portions thereof adapted to allow them to embrace the winged cylindrical rail member 2, as shown, are brought inwardly into engagement with the wire. This movement occurs by action upon a suitable slide 12 to which these forming members are pivoted as indicated at 11. 15 A spring, such for example, as shown at 13 may cause these members 10 to normally stand apart, and upon the inward movement cam portions formed rigid on the anvil block 1 engage the coacting surfaces 14 on the forming members 10 and cause them to move inwardly closely embracing the rail member 2. As the slide 12 moves inwardly to bring the forming member 10 into engagement with the wire and the rail 2, a 20 suitable cutter, such as indicated at 3 carried by the slide, severs the wire at the end of the guide 15 for the exact length needed for the clip. This action is shown in Fig. 2, where the cutting takes place just as the formers engage the wire. Grooves 7 on the forward faces of the formers hold the wire in position against the rail 2 and the further movement of these formers wraps the wire around the rail, forming the loop L of the clip, but leaving the ends thereof projecting laterally in the same plane along grooves 6 in the anvil 5.

The next step is the inward movement of formers indicated at 22 as carried upon a 40 suitable lateral slide 20, moving in the direction parallel with and in substantially the same plane as the slide and formers 10 and 12. These are shown as pivoted to the slides and have suitable springs as indicated, 45 for example, at 21, to hold them normally outwardly and they are guided across an extension 24 of the block or anvil 1, while projections 25 engage cam surfaces 26, with the result that as these are brought inwardly 50 they also close together, and the inner ends are notched to fit around the ends of the former 10, thus turning the ends of the wire back upon itself forming the wire to the shape shown in Fig. 10. It is necessary to 55 withdraw the die members 22 a sufficient distance to free the now L-shaped ends of the wire and to clear the path of slide members about to be described. This is done by drawing the slide 21 rearwardly, allowing 60 the die 22 to be forced outwardly by the springs 21, the cam 26 sliding past the abutment 25 so that the die 22 moves toward its original starting position.

Now the clip is still all in one plane and 65 the next step is to swing the ends of the

substantially double U-shaped member upwardly, that is, move the outer ends upwardly to form the laterally extending loops M. This is done by the upward movement of the slide members 30 extending through 70 the block 1, and causing the wire to turn upwardly from the grooves 6 on the anvil member 5, rigid with the block 1. This upward movement is indicated in Fig. 5. The clip then has the form shown in Fig. 11. 75

Now to complete the loop M, still leaving the ends of the loop as before, side die members 40 are brought inwardly still acting against the forming member 5, rigid with the block 1, while holding the wire in the grooves 6, 7 and 8 of the formers 10 and 5. These dies 40 may come inwardly from directions at right angles to the directions of movement of the slides and formers just described. Such dies are indicated as bifurcated members having the notched ends adapted to engage the wire as shown in Fig. 7, and carried on suitable slides, one of which is indicated at 42.

During the inward movements of these die members 40, the members 30 are in their uppermost position and the members 10 have not yet been released, so that the wire is firmly held in all directions except that of permitting the ends which are to become 95 the spring clamping portion O of the clip, to be swung inwardly as indicated in Figs. 6 and 7.

Now while so held, and without a loss of time, it is one of the purposes of the present 100 invention to bend these end clips O downwardly intermediately of their length to facilitate sliding the terminal member thereunder, as previously described, simultaneously with the completion of the inward 105 movement of the slide members 40. To accomplish this, I form a bifurcated member 50 above the anvil and cause it to move upwardly and downwardly, and as it is brought downwardly, it straddles the rail 2 and its rounded lower ends engage the ends of the wire which are now lying across the clamping and forming members 10 and against the rail 2 bending the wire downwardly into 110 grooves or notches, shown at 53, in the members 10, just as the members 40 complete 115 their inward movement, thus forming the ends of the wire into lateral curves about the rail. This operation is indicated in Fig. 8, the parts clamping the clip being there 120 illustrated in the closed position before releasing.

These parts are then all withdrawn, the slide 51 moving upwardly, the slide 12 moving backwardly with its member 10, and the two forming members 40 moving outwardly at the opposite sides, and to remove the clip, the rail 2 is slid downwardly through the block 1, permitting it to spring outwardly, whereupon the wire is again fed 125 130

to the dies and the rail 2 returns and the operation is repeated.

It has been found that these steps may be accomplished in very rapid succession, 5 the entire clip with its curved ends being finished in one group of forming dies of this character, and while forming in two, three or even four directions, has been frequently done before, it is believed to be 10 novel to use dies and to accomplish forming steps by moving forming members in four directions in one plane and in directions at right angles thereto upwardly and downwardly with relation to that plane to 15 form such combinations of curved portions as those of the member O of the clip described.

Having thus described my invention, I claim:—

20 1. The process of forming a wire clip including the steps of bending the mid portion of a wire by the inward movement of dies into an open loop in a horizontal plane, turning the ends at right angles in the same 25 plane and in the same direction with the loop, bending the portions between the loop and the ends into two oppositely facing loops in a vertical plane, bending the ends into two semi-circular bends, each facing 30 the other in a horizontal plane, and lying coincident with the first named loop and spaced above it, crimping the central portions of said last named horizontal bends in a direction toward the first named loop, and 35 releasing the wire so formed by a simultaneous outward movement of the dies then engaging the wire.

2. The process of forming a terminal retaining clip, having loops in three planes, 40 two of which are parallel and at right angles to the plane of the connecting portion, consisting of bending the original loop about a stationary form and holding the bend thus made, bending the free ends of the 45 wire while so held backward in the direction of the loop in the same plane, bending

the wire in a second plane intermediate the outer bends and the loop, thus bringing the free ends into the third plane, and thereafter simultaneously forming the free 50 ends into circular bends in that plane, each facing the other and crimping part of the circular bends out of said last named plane.

3. The process of forming a wire clip including the steps of bending the mid-portion 55 of a wire into an open loop in a given plane, turning back the ends of the wire in the same plane and in the same direction of the loop, bending the wire in a second plane intermediate the outer bends and the loop to 60 bring the free ends into a third plane parallel to the plane of the loop, and thereafter crimping the said free ends.

4. The process of forming a wire clip including the steps of bending the mid-portion 65 of a wire into an open loop in a given plane, turning back the ends of the wire in the same plane and in the same direction of the loop, bending the wire in a second plane intermediate the outer bends and the loop 70 to bring the free ends into a third plane parallel to the plane of the loop, and thereafter curving the free ends to approximate a loop lying in the said third plane.

5. The process of forming a wire clip 75 including the steps of bending the mid-portion of a wire into an open loop in a given plane, turning back the ends of the wire in the same plane and in the same direction of the loop, bending the wire in a second 80 plane intermediate the outer bends and the loop to bring the free ends into a third plane parallel to the plane of the loop, and thereafter curving the free ends to approximate a loop substantially coinciding with 85 and lying parallel to said first named loop, and finally crimping one of said loops toward the other.

In testimony whereof, I hereunto affix my signature.

JOHN A. HOFFMAN.
